HYDRAULICALLY OPERATED STEADYREST

Raymond A. Cole, Worcester, Mass., assignor to
Norton Company, Worcester, Mass., a corpora-
tion of Massachusetts

Application November 18, 1935, Serial No. 50,276

7 Claims. (Cl. 51—238)

This invention relates to grinding machines, and more particularly to a hydraulically operated steadyrest for steadyng and supporting the work during a grinding operation.

5 One of the objects of this invention is to provide a simple and thoroughly practicable hydraulically actuated steadyrest. Another object is to provide a hydraulically operated steadyrest which is compact in construction and simple 10 in operation and action during the grinding operation. Other objects will be in part obvious or in part pointed out hereinafter.

The invention accordingly consists in the features of construction, combinations of elements, 15 and arrangements of parts, as will be exemplified in the structure to be hereinafter described and the scope of the application of which will be indicated in the following claims.

In the accompanying drawings, in which is 20 shown one of various possible embodiments of the mechanical features of this invention,

Fig. 1 is an end elevation of the improved steadyrest having a portion broken away to more clearly show the construction;

25 Fig. 2 is a fragmentary detail view showing the manual adjustment of the steadyrest shoe;

Fig. 3 is a plan view of the steadyrest having a portion broken away and shown in section to more clearly show the construction;

30 Fig. 4 is an enlarged cross sectional view, on an enlarged scale, taken approximately on the line 4—4 of Fig. 3; and

Fig. 5 is an enlarged cross sectional view, taken approximately on the line 5—5 of Fig. 3, showing the fluid inlet chamber, the needle valve and the ball check valve.

A steadyrest has been illustrated as mounted on a grinding machine in the usual manner. A 40 rotatable grinding wheel 10 is supported on a wheel slide, not shown, and arranged to be moved into operative grinding relation with a rotatable work piece 11. A longitudinally movable work table 12 is provided for supporting the work piece 11 on the usual rotatable work supports such as a 45 head and footstock, not shown. A steadyrest base or frame 15 is mounted on the table 12 and is provided with mating surfaces 16 and 17 which are arranged to mate and fit upon the upper surface of the table 12. The base 15 is arranged to be clamped in rigid engagement with the table 12 by means of a pair of clamping members 18 which are arranged to engage a dovetailed surface 19 on the table 12. The upper ends of the clamping members are screw threaded and provided with clamping nuts 20 which may be

turned to lock the steadyrest base 15 into rigid engagement with the table 12.

The steadyrest base 15 is provided with an upwardly extending portion 25 which serves to support a horizontally slidable member 26 carrying a work steadyng shoe 27 which is preferably arranged to engage the work piece at a point diametrically opposite the line of contact between the grinding wheel and the work piece.

The projection 25 of the base 15 also slidably 10 supports a horizontally slidable rod 30 which is connected by a stud 31 with a pivotally mounted steadyrest member 32 carrying a second work steadyng shoe 33. The member 32 is pivotally mounted on a stud 34 on the base 15 and is ar- 15 ranged to swing the shoe 33 toward or from the axis of the work piece 11. The steadyrest shoe 33 is preferably arranged to engage the work piece at a point below the work axis and at a point ad- 20 jacent to the line of contact between the grinding wheel and the work piece so as to steady the work piece 11 during the grinding operation against the downward grinding thrust of the wheel 10.

In order to move the steadyrest shoes 27 and 25 33 rapidly into and out of an operative position with relation to the work piece 11, a suitable fluid pressure actuated mechanism is provided and in the preferred arrangement in order to provide a compact construction which does not project 30 toward the front of the machine to interfere with the operator's control of the machine, a fluid pressure mechanism is provided in which the fluid pressure cylinders are arranged in a vertical manner. As illustrated in the drawings, the 35 steadyrest base 15 has a downwardly extending projection 40 which is provided with a pair of vertically arranged cylinders 41 and 42. Each of the cylinders 41 and 42 is provided with a slid- 40 ably mounted piston 43 and 44 respectively, each of which is provided with an upwardly extending piston rod 45 and 36 respectively. In order that the vertical motion of the piston rods 45 and 36 may be transmitted to cause a horizontal motion of the rods 26 and 30, a suitable linkage is pro- 45 vided between the piston rods and the slidable rods 26 and 30. A bell crank lever 46 is pivotally mounted on a stud 47 and has a horizontally ex- 50 tendsing arm 48 which is provided with a yoked end 49. The yoked end 49 is arranged to fit within a slot 50 in the upper end of the piston rod 36 and to straddle a pin 51 which is carried by the piston rod 36 so that a vertical movement of the piston 44 is transmitted through piston rod 36, pin 51 and the yoked end 49 to rock the 55

bell crank lever 46 about its pivot 47. The bell crank 46 is provided with a vertically extending arm 52 which is yoked and arranged to straddle a spool 53.

5 The yoked arm 52 of the bell crank 46 is provided with pins 54 and 55 which ride in a groove 56 in the spool 53 so that a rocking motion of the bell crank 46 serves to move the spool 53 endwise in a horizontal direction.

10 The spool 53 is connected to move the horizontally movable rod 26 which supports the shoe 27. In order to permit a manual adjustment of the steadyrest shoe 27 relative to the hydraulic movement thereof by means of the piston 44, a 15 manual adjusting means is interposed between the piston 44 and the shoe 27. In the preferred construction the spool 53 is formed as an integral part of a nut 58 which is screw threaded onto a reduced threaded portion 59 of the member 26. 20 By turning the nut 58 by means of a knurled knob 60, the shoe 27 may be adjusted relative to the bell crank 46 and the piston 44. A lock screw 61 is threaded into the nut 58 and is provided with a knurled knob 62 by means of which 25 the nut 58 may be locked in adjusted position on the screw 59.

The piston rod 45 is connected so that its vertical motion serves to cause a horizontal endwise movement of the rod 30 to swing the steadyrest shoe 33 either into or out of engagement with the work piece 11. This is preferably accomplished by means of a bell crank 70 which is pivotally mounted on a stud 71. The bell crank 70 is provided with a horizontally extending arm 72 having a yoked end portion 73 arranged to straddle a pin 74 carried by the upper end of the piston rod 45. The yoked member 73 is arranged to fit within a slot 75 in the upper end of the piston rod 45, so that any vertical motion of the piston rod 45 is transmitted to rock the bell crank lever 70. The bell crank 70 is provided with a downwardly extending arm 76 which is yoked at its lower end and is provided with a pair of opposed pins 77 which engage a rotatable collar 78. Movement of the piston rod 45 serves through pin 74 and yoked member 73 to rock the bell crank 70 about its pivot 71, so as to move the rotatable collar 78 endwise. The collar 78 is rotatably supported on a nut 79 which is screw threaded onto a screw threaded portion 80 of the rod 30. The rotatable collar 78 is held against endwise movement by means of a flange 81 on the nut 79 on one side and by means of a sleeve 82 which fits on a reduced portion 83 of the nut 55 79 and is held in an operative position thereon by means of a pair of opposed pins 84 and 85. The sleeve 82 is provided with an outwardly extending portion 86 having a knurled adjusting knob 87 to permit the nut 79 to be readily adjusted from the front of the steadyrest so as to move the rod 30 endwise in either direction to rock the arm 32 and cause the steadyrest shoe 33 to move either into or out of engagement with the work piece 11. The adjusting sleeve 82, extension 65 86 and knob 87 are provided with an internal threaded aperture. A locking screw 88 is threaded into the aperture within the member 86 and is provided with a knurled adjusting knob 89. The screw 88 is arranged to engage the end of 70 the threaded portion 80 of the rod 30 so that after the nut 79 has been adjusted to the desired extent, the screw 88 may be turned by knob 89 to lock the screw 80 and the nut 79 into a fixed relationship with each other.

75 The nut and screw adjusting devices between

the steadyrest shoes 27 and 33 and pistons 44 and 43 serve to permit an adjustment of the position of the shoes 27 and 33 relative to the fluid pressure pistons 44 and 43 respectively in setting up the machine for a given size work piece.

Fluid under pressure is supplied from any suitable source, such as a fluid pressure pump on the grinding machine or from an outside source. Fluid under pressure passing through a pipe 90 enters a fluid chamber 91 in the downwardly extending portion 40 of the steadyrest base 15. Fluid under pressure entering the chamber 91 passes through a port 92 and through an adjustable needle valve 93, through a downwardly extending passage 94 in the frame 40 and through a transversely extending passage 95, in a lower cylinder head 96, into a cylinder chamber 42 to cause the piston 44 to move upwardly into the position illustrated in Figs. 1 and 4. This motion serves through the piston rod 36, the pin 51, 20 the yoked member 49, to rock the bell crank lever 46 in a clockwise direction (Fig. 1) to cause the rod 26 to move the shoe 27 into operative engagement with the work piece 11.

Similarly, fluid under pressure within the passage 91 passes through a port 98, through a needle valve 99 and downwardly through a vertical passage 100 within the projection 40 of the steadyrest base 15 and then is forced through a transversely extending passage 101 to cause the piston 30 43 to move upwardly which serves through the piston rod 45, the pin 74, the yoked member 73, to rock the bell crank lever 70 in a clockwise direction so as to move the rod 30 (Figs. 1 and 2) toward the left which in turn serves to rock the steadyrest shoe support 32 in a counterclockwise direction to move the steadyrest shoe 33 into operative engagement with the work piece 11.

In order that the steadyrest shoes may be withdrawn rapidly from engagement with the work after the work piece has been ground to a predetermined size, a separate exhaust passage is provided to permit a rapid exhaust of fluid from the cylinder chambers 41 and 42. A transversely extending passage 105 leads from the cylinder 45 chamber 42 to a vertically extending passage 106 in the member 40 which is covered by a ball check valve 107. During the period when fluid under pressure is admitted to the chamber 91, the ball 107 is held in a fixed position on its seat 108 so that fluid cannot pass through the passages 106 and 105 but must be forced through the port 92 and needle valve 93 at a controlled rate. When the pressure is cut off from the passage 91 and fluid contained within the passage 91 is permitted 55 to exhaust therefrom, fluid under pressure within the cylinder chamber 42 is allowed to pass through passage 105, passage 106, and to raise the ball 107 from its seat 108 and allow the exhaust fluid to enter passage 91 and to exhaust therefrom.

Similarly, a transverse passage 108 is provided which extends transversely from the cylinder chamber 41 and connects with a vertically extending passage 109, the upper end of which is closed by a ball check valve 110 having a seat 111 to close the passage 109 when pressure is admitted to the chamber 91. The ball 110 serves to permit exhaust of fluid from the cylinder chamber 41 when pressure is released from the passage 91.

In order that the steadyrest shoes 27 and 33 may be rapidly removed to an inoperative position when the fluid pressure is cut off from the chamber 91 and the fluid is allowed to exhaust from the cylinder chambers 41 and 42 and the 75

chamber 91, a yieldable spring is provided to rapidly exhaust the fluid and move the shoes 27 and 33. A spring 116 surrounds the piston rod 45 and is contained within an aperture 117 in the piston 43 and is interposed between a surface 118 on the piston 43 and a cylinder head 119. The spring 116 exerts a downward pressure on the piston 43 to rapidly exhaust fluid from the cylinder 41 when the pressure is cut off to rapidly withdraw the shoe 33 to an inoperative position.

Similarly a spring 120 surrounds the piston rod 36 and is contained within an aperture 121 on the piston 44 and is interposed between a surface 122 on the piston 44 and the cylinder head 114. The spring 120 exerts a downward pressure on the piston 44 to rapidly exhaust fluid from the cylinder chamber 42 when the pressure is cut off to rapidly withdraw the shoe 27 to an inoperative position.

20 The piston rod 36 is provided with a projection 112 which carries an adjustable stop screw 113 which serves to engage a cylinder head 114 at the upper end of the cylinder 42 and serves to limit the downward movement of the piston 44, thus permitting an adjustment of the extent of withdrawal of the horizontally movable shoe 27. The adjusting screw 113 is provided with a lock nut 115 which serves to lock the screw in a predetermined adjusted position.

30 The piston rod 45 is provided with a projection 125 which carries an adjustable stop screw 126 which serves to engage a projection 128 of the cylinder head 119 and serves to limit the downward movement of the piston 43, thus permitting an adjustment of the extent of withdrawal of the pivotally mounted shoe 33. The adjusting screw 126 is provided with a lock nut 127 which serves to lock the screw 126 in a predetermined adjusted position. By manipulating the adjusting screws 113 and 126, the lost motion or withdrawal of the steadyrest shoes 27 and 33 respectively may be varied in accordance with the requirements of the particular grinding job.

In the operation of this improved steadyrest, the fluid under pressure is admitted to the passage 91 to cause the pistons 43 and 44 to move upwardly to move the shoes 33 and 27 into operative engagement with the work piece 11 to support and steady the same during the grinding operation. By manipulation of the needle valves 93 and 99, the passage of fluid under pressure into the cylinder chambers 41 and 42 may be varied so that either the piston 43 or the piston 44 may be moved so as to cause either the shoe 27 or the work steadyrest shoe 33 to be moved into engagement with the work piece before the other shoe contacts therewith. In the preferred operation of the steadyrest, however, it is desirable to move the steadyrest shoe 33 into operative position to engage the under side of the work piece 11 to support the same against the rotary thrust of the grinding wheel 10 before the horizontally movable shoe 27 is moved into supporting engagement therewith. This may be accomplished by adjusting the needle valve 93 so that fluid may pass through this valve quicker than it can pass through the other needle valve 99.

In setting up the steadyrest for grinding a work piece of a predetermined size, the operator 70 first slacks off the locking screws 61 and 88 by turning the knob 62 and 89. Then by manipulation of the knurled knobs 60 and 87, the work steadyrest shoes 27 and 33 may be adjusted as desired. After this adjustment has been made, 75 the lock screws 61 and 88 are then locked to

maintain the parts in the fixed adjusted position.

In the preferred operation of the improved steadyrest, the work steadyresting shoes 27 and 33 are moved into operative engagement with the periphery of the work piece being ground under the influence of fluid pressure within the cylinder chambers 42 and 41 respectively, and the shoes 27 and 33 are maintained with a predetermined uniform pressure in operative steadyresting engagement with the work piece 11 as the grinding operation proceeds by the fluid pressure mechanism. In setting up the steadyrest for grinding a given piece of work, a work piece of the finished size may be placed in the machine, fluid under pressure is admitted through the passages 90 to move 15 the pistons 43 and 44 into their upward positions, as illustrated in Fig. 4. When the pistons are in their upward position, the shoes 27 and 33 are then adjusted into the desired supporting relationship with the work piece by manipulation 20 of the adjusting knobs 60 and 87. Then the adjusting screws are locked in adjusted position and the fluid is cut off from the passage 91, allowing the fluid contained therein and in the cylinder chambers 41 and 42 to exhaust so as to 25 permit the work steadyresting shoes 27 and 33 to move out of operative contact with the work piece 11.

If desired, the steadyresting shoes may be brought into an operating position by means of the fluid 30 pressure mechanism, that is, the shoes may be adjusted so that the pistons 43 and 44 will engage the upper ends of the cylinders when the work steadyresting shoes 27 and 33 are about to engage the surface of the work piece 11 to be ground. 35 Then the shoes may be adjusted manually by means of the knobs 60 and 87 to maintain the shoes in the desired supporting relationship with the work piece 11 during the grinding operation.

It will thus be seen that there has been provided by this invention apparatus in which the various objects hereinabove set forth together with many thoroughly practical advantages are 40 successfully achieved.

As many possible embodiments may be made of 45 the above invention and as many changes might be made in the embodiment above set forth, it is to be understood that all matter hereinbefore set forth, or shown in the accompanying drawings, is to be interpreted as illustrative and not in a 50 limiting sense.

I claim:—

1. A steadyrest for a grinding machine comprising a base, means to support said base on a grinding machine, a horizontally movable shoe arranged to engage the work opposite the grinding wheel, a pivotally mounted shoe arranged to engage the work at a point below the work axis and adjacent to the line of contact between the wheel and work, means including a vertically arranged fluid pressure piston and cylinder, a bell crank lever interposed between the piston and shoe whereby vertical movement of said piston moves said shoe horizontally into or out of operative relation with the work, a second vertically arranged piston and cylinder, and a second bell crank interposed between said piston and the pivotally mounted shoe whereby vertical movement of said piston is transmitted to swing the lower steadyrest shoe into or out of operative relation with the work piece. 60

2. A steadyrest for grinding machines comprising a base, means to support said base on the grinding machine, a horizontally movable work steadyresting shoe arranged to engage the work op- 75

posite the grinding wheel, a pivotally mounted shoe arranged to engage the work at a point below the work axis and adjacent to the line of contact between the wheel and work, means including a vertically arranged piston and cylinder to move said horizontally movable shoe into or out of operative relation with the work, means interposed between the piston and steadyrest shoe to adjust the position of the shoe relative to said piston movement, a second fluid pressure piston and cylinder operatively connected to swing the lower shoe into or out of operative relation with the work piece, and adjusting means interposed between the piston and steadyrest shoe to permit adjustment of the lower steadyrest shoe relative to its actuating piston.

3. A steadyrest for grinding machines comprising a base, means to support said base on the grinding machine, a horizontally movable work steadyng shoe arranged to engage the work opposite the grinding wheel, a pivotally mounted shoe arranged to engage the work at a point below the work axis and adjacent to the line of contact between the wheel and work, means including a vertically arranged fluid pressure piston and cylinder to move said horizontally movable shoe into operative relation with the work, means interposed between the piston and steadyrest shoe to adjust the position of the shoe relative to said piston, a second fluid pressure piston and cylinder operatively connected to swing the lower shoe into operative engagement with the work piece, means interposed between the second piston and the pivotally mounted shoe to permit adjustment of the second shoe relative to its actuating piston, a fluid pressure chamber within the base, and an adjustable needle valve interposed between said chamber and each cylinder to independently adjust the admission of fluid pressure to said cylinders.

4. A steadyrest for grinding machines comprising a base, means to support said base on a grinding machine, a horizontally movable shoe arranged to engage the work opposite the grinding wheel, a pivotally mounted shoe arranged to engage the work at a point below the wheel axis and adjacent to the line of contact between the wheel and work, means including a vertically arranged piston and cylinder, a bell crank lever interposed between the piston and shoe whereby vertical movement of the piston moves the shoe horizontally into or out of operative relation with the work, a second vertically arranged piston and cylinder, a second bell crank lever interposed between the second piston and the pivotally mounted shoe whereby the vertical movement of said piston is transmitted to swing the lower steadyrest shoe into or out of operative relation with the work piece, a fluid pressure chamber within said base, and adjustable valves interposed between said chamber and each of said cylinders to independently adjust the pressure of the steadyrest shoes against the work.

5. A steadyrest for grinding machines comprising a base, means to support said base on the grinding machine, a horizontally movable shoe arranged to engage the work opposite the grinding wheel, a pivotally mounted shoe arranged to engage the work at a point below the work axis and adjacent to the line of contact between the wheel and work, means including a vertically arranged fluid pressure piston and cylinder, a bell crank lever interposed between the piston and shoe whereby vertical movement of the piston moves said shoe horizontally into or out of op-

erative relation with the work, manually operable adjusting means interposed between the bell crank lever and shoe to permit adjustment of the shoe relative to the piston, a second vertically arranged piston and cylinder, a second bell crank lever interposed between the piston and the pivotally mounted shoe whereby the vertical movement of said second piston is transmitted to swing the lower steadyrest shoe into or out of operative relation with the work, and a manually operable adjusting means interposed between the second bell crank and the pivotally mounted shoe whereby the second shoe may be adjusted relative to its actuating piston.

6. A steadyrest for a griding machine comprising a base, means to support said base on the griding machine, a horizontally movable shoe arranged to engage the work opposite the griding wheel, a pivotally mounted shoe arranged to engage the work at a point below the work axis and adjacent to the line of contact between the wheel and work, means including a vertically arranged fluid pressure piston and cylinder, a bell crank lever interposed between the piston and shoe whereby vertical movement of the piston moves said shoe horizontally into or out of operative relation with the work, manually operable adjusting means interposed between the bell crank lever and shoe to permit adjustment of the shoe relative to the piston, a second vertically arranged piston and cylinder, a second bell crank lever interposed between the piston and the pivotally mounted shoe whereby the vertical movement of said second piston is transmitted to swing the lower steadyrest shoe into or out of operative relation with the work, a manually operable means interposed between the second bell crank and the pivotally mounted shoe to facilitate adjustment of the pivotally mounted steadyrest shoe and its actuating cylinder, a fluid pressure chamber within said base, and a valve interposed between said chamber and each of the cylinders to independently adjust the fluid under pressure entering each of said cylinders to independently control the movements of each of the steadyrest shoes.

7. A steadyrest for a grinding machine comprising a base, means to support said base on the grinding machine, a horizontally movable shoe arranged to engage the work opposite the grinding wheel, a pivotally mounted shoe arranged to engage the work at a point below the work axis and adjacent to the line of contact between the wheel and work, means including a vertically arranged fluid pressure piston and cylinder, a bell crank lever interposed between the piston and shoe whereby vertical movement of the piston moves said shoe horizontally into or out of operative relation with the work, manually operable adjusting means interposed between the bell crank lever and shoe to permit adjustment of the shoe relative to the piston, a second vertically arranged piston and cylinder, a second bell crank lever interposed between the piston and the pivotally mounted shoe whereby the vertical movement of said second piston is transmitted to swing the lower steadyrest shoe into or out of operative relation with the work, and means including a pair of ball check valves interposed between said chamber and each of said cylinders to facilitate rapid exhaust of fluid from said cylinders to move the steadyrest shoes rapidly to an inoperative position.
